STRIP FEEDING APPARATUS

Albert W. Metzner, Dayton, Ohio, assignor to The Standard Register Company, Dayton, Ohio, a corporation of Ohio

Application October 20, 1950, Serial No. 191,289

13 Claims. (Cl. 197—133)

1

This invention relates to strip feeding apparatus, and more particularly to a positive pin type feeding apparatus for advancing a strip of recorded material about a platen roll in a typewriter or like machine.

Pin feed devices in such machines have heretofore been known but in a form requiring the use of a special platen or of modified carriage arrangements.

The instant invention contemplates the avoidance of these disadvantages having as one object thereof pin feeding from the outer surface of a standard typewriter or writing machine platen.

Another object of the invention is to provide a pin feed mechanism which can be applied to any conventional platen without the necessity of altering or substituting parts in the machine.

A further object of the invention is to provide for longitudinal adjustment of the pin feed devices along the platen so that they may be shifted out of position to the end of the platen, or removed from the platen, or relocated in correspondence with various width record strips.

A further object of the invention is to provide means for projecting the feeding pins relative to the platen roll in a localized area for feeding engagement with an overlying record strip.

A still further object of the invention is to permit circumferential adjustment of the area in which the pins extend from the platen to thereby provide an inoperative position in which the pins are unable to engage and feed the strip, and vice versa.

A further object of the invention is to provide a strip feeding apparatus embodying the advantageous structural features and inherent meritorious characteristics and mode of operation herein described.

With the above primary and other incidental objects in view as will more fully appear in the specification, the invention intended to be protected by Letters Patent consists of the features of construction, the parts and combinations thereof, and the mode of operation, as herein-after described or illustrated in the accompanying drawings, or their equivalents.

In the drawings wherein is illustrated the preferred but not necessarily the only form of embodiment of the invention,

Fig. 1 is a fragmentary perspective view of a typewriter with the feed devices of the present invention installed thereon;

Fig. 2 is a fragmentary enlarged view, in perspective, of the platen and feed device thereon, with the device feeding the record strip;

2

Fig. 3 is a view similar to Fig. 2 with the record strip removed;

Fig. 4 is a view in front elevation of a platen equipped with the feed devices of the invention;

5 Fig. 5 is a view in cross section taken substantially along the line 5—5 of Fig. 4;

Fig. 6 is a view similar to Fig. 5, showing the feed device adjusted to inoperative position;

10 Fig. 7 is a view in cross section taken substantially along the line 7—7 of Fig. 4;

Fig. 8 is a detail view in longitudinal section, taken substantially along the line 8—8 of Fig. 6;

15 Fig. 9 is an enlarged view in cross section, taken substantially along the line 9—9 of Fig. 4;

Fig. 10 is an enlarged detail view, similar to Fig. 7, showing the manner of locking the pin feed devices to the platen;

Fig. 11 is a detail view in front elevation of a cam ring comprised in the pin feed device; and

20 Fig. 12 is a detail view, in perspective, of a pin and crank rod therefor comprised in the pin feed mechanism.

Like parts are indicated by similar characters of reference throughout the several views.

25 Referring to the drawings, the invention is disclosed as applied to a typewriter 15 (Fig. 1) presenting a platen 16 about which continuous record material 17 is fed circumferentially, the record material having marginal perforations 18 for accurate feeding and aligning thereof. The platen 16 is supported for rotary motion by side plates 19, extensions of which support cross rods 21, 22 and 23 for guiding the record strip to and from the platen.

30 In such a machine as conventionally constructed and arranged, the instant invention proposes the installation of adjustable and demountable pin feed devices on the platen engageable with the perforations 18 to advance the record material in response to rotation of the platen. There is a pair of such feed devices, one adjacent each end of the platen and since they are identical a description of one will suffice for both.

35 Each comprises a basic or underlying cylindrical band 24 (see Fig. 9) which has a snug fit upon the rubber or rubber-like outer sleeve of the platen, the band being slidable, however, longitudinally of the platen. The outer edge of the band 24 is overlaid by a relatively narrow loop 25 having a pair of diametrically opposed spring arms 26, the outer ends of the arm being formed as hooks arranged to pass through suitable holes in the band 24 and be anchored in the platen 16. When so anchored, the spring arms 50 26 prevent motion of the band 24 and loop 25

relatively to the platen. The spring arms tend to assume a retracted disengaged position as shown in Fig. 10. They are controlled, however, by a knurled collar 27 which loosely surmounts the loop 25. The collar 27 has circumferential transverse slots 28 brought selectively into registry with the spring arms 26 by a relative rotation of the collar. So positioned, the collar 27 exposes the spring arms 26 which, with little or no assistance, are withdrawn from engagement with the platen. Continued rotation of the collar 27 produces a camming action upon the arms 26, driving the hooked ends thereof into the platen. If the collar 27 then is released, in a position with the slots 28 out of registry with the arms 26, the arms are locked in position anchoring the band 24 to the platen.

The band 24 is surrounded by a second cylindrical band 29 which is in effect an integral part of the band 24, being riveted or otherwise secured thereto for unison movement. The band 29 has a continuous series of circumferentially spaced, longitudinal bosses 31 in which crank rods 32 (Fig. 12) are installed for oscillatory movement. At about its mid point each rod 32 has an integrally formed tongue or pin 33 extending perpendicularly to the axis of the rod. Sockets 34, struck up out of the material of the band 29 are arranged to receive the pins 33, the pins being movable from an inactive position wherein they lie in the sockets 34 to an active position wherein they project radially outward substantially at right angles to the periphery of the band.

The pins 33 are raised and lowered by a rocking motion of the crank rods 32 obtained through the cooperation of the rods with a cam ring 35 (see particularly Fig. 11). The cam ring 35 comprises a substantially crescent shaped member 36 having an arcuate slot 37 in one side face thereof. Secured to the inner and outer edges of the member 36 are bands 38 and 39 spaced apart to define therebetween a slot 41. The slot 41 merges with and forms a continuation of the slot 37, it being noted however, that the slot 37 is eccentric with respect to the axis of the bands 38 and 39 while the slot 41 is concentric.

The cam ring 35 loosely surmounts the band 24, it being free for rotary motion relative thereto. It is, however, held against relative axial motion by being confined between the loop 25 and circumferentially spaced apart upstanding lugs 42 on the outer end of band 29. The cam groove defined by registering slots 37 and 41 receives the offset ends of crank rods 32. As a result, relative rotary motion between the cam ring 35 and the platen 16 causes the pins 33 to be successively raised and lowered as the crank ends of rods 32 reach and pass through eccentric portion 37 of the cam groove.

The crescent shaped member 36 has an upstanding ear 43 arranged to be connected by a releasable plunger 44 to an arm 45 pivotally mounted on the cross bar 21. By rotary adjustment thereof the cam ring may be selectively located for connection with any one of a series of openings 46 in the arm 45 or with an opening 47 therein. Such adjustment will of course alter the phase relationship between the cam ring and the platen, resulting in the pins 33 being raised and lowered in an earlier or later phase of rotation of the platen.

In the operation of the pin feed devices, the record material 17 is fed circumferentially about the platen 16, as shown in Fig. 5, with the margins of the record material overlying the pins 33 on

the bands 29. During the major part of the travel of the platen, the pins 33 remain inactive in their sockets 34. As the pins approach the eccentric slot 37, however, the crank rods 32 carrying the pins ride up in the slot 37 and so rock the pins 33 to an upright position. In the course of such motion the pins enter and engage an associated perforation 18 in the record material, and, as their motion through slot 37 is continued, exert successive pulling or feeding impulses on the record strip. The strip accordingly is advanced in unison with advancement of the platen and is positively held against relative shifting motion in either a lateral or rotative sense.

By the selection of a particular opening 46 the pins 33 are projected and withdrawn in a selected circumferential area of the platen, the arrangement ordinarily preferred being one in which the pins 33 occupy their most nearly erect position on a line a little above the horizontal line along which the platen is struck by the type as shown in Fig. 5. A rotary adjustment of the cam ring 35 to a connection with opening 47 in arm 45 in effect disables the pin feed devices. As shown in Fig. 6, in this position of the parts the circumferential area in which the pins 33 are extended is in approximately vertical overlying relation to the platen or some distance removed from the writing line. Since the record strip begins to leave the platen immediately after it leaves the writing line, the relatively remote area of projection of the pins 33 accordingly results in the pin being unable to engage the perforations 18 in the strip.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise but one of several modes of putting the invention into effect.

Having thus described my invention, I claim:

1. In a typewriter or like device utilizing a rubber or rubber-like platen, a pin feed mechanism including spaced apart bands frictionally engaging the platen, feed pins carried by said bands, and a spring clip surrounding each band and formed with prongs to be pressed through openings in the band and into the platen to anchor the band to the platen.

2. A typewriter or like device according to claim 1, characterized by rings loosely surmounting said spring clips and formed with openings to be brought selectively to registry with said prongs whereby said prongs may be released for relative adjustment of said bands along the platen.

3. In a typewriter or like device utilizing a rotatable platen in the feeding of marginally punched record material, pin feed devices including tilttable pins carried on the periphery of said platen, and cam rings surrounding said platen and engageable with said pins for tiltting said pins into and out of cooperative relation

with the marginal punchings in the record material in response to rotation of the platen.

4. In a typewriter or like device wherein perforate record material is fed circumferentially over a rotatable platen, a pin feed device for the material including a band releasably attached to the platen for rotation therewith, pins carried by said band for engaging and feeding the record material, and a cam in peripheral surrounding relation to the platen and cooperable with the pins to effect an engageable and disengageable relation of the pins with respect to the record material in a predetermined phase relationship to the rotation of the platen.

5. A typewriter or like device, according to claim 4, characterized in that said cam is adjustable to vary the described phase relationship.

6. In a typewriter or like device wherein perforate record material is fed circumferentially over a rotatable platen, a pin feed device including a band releasably attached to the platen for rotation therewith, pins carried by said band in circumferentially spaced relation for motion into and out of a projecting position wherein they are engageable with the record material, and a cam externally of the platen cooperative with said pins to move said pins sequentially into and out of said projecting position in response to rotation of the platen and in a timed relation thereto.

7. In a typewriter or like device wherein perforate record material is fed circumferentially over a rotatable platen, a pin feed device including a band releasably attached to the periphery of the platen for rotation therewith, circumferentially spaced pins carried by said band for swinging motion between an inactive position substantially parallel to the periphery of the band and an active position substantially perpendicular to the band, a cam ring surrounding the platen and fixed relative thereto, and interengaging portions on said pins and cam ring for moving said pins in predetermined phase relationship to the rotation of the platen.

8. In a strip feed apparatus, a cylindrical band for installation on a typewriter platen or like rotatable feed shaft, circumferentially spaced pins carried by said band for pivotal motion to and from a projecting substantially perpendicular position with respect to the band, a relatively stationary cam ring in side-by-side relation to said band, and interengaging portions on said pins and cam ring for moving said pins in a timed relation to the movement of the platen.

9. A strip feed apparatus, according to claim 8, characterized by means for rotatively adjusting said cam ring to vary the position circumferentially of the platen wherein said pins reach perpendicular position.

10. In a pin feed device, a cylindrical band to be slidably mounted on a typewriter platen or the like, means for releasably securing said band to the platen, pins carried by said band for pivotal motion to and from a projecting substantially perpendicular position with respect to the band, a cam ring to be rotatably mounted on said platen in a side-by-side relation to said band, said cam ring presenting a slot which is concentric with the band over a part of its circumference and eccentric over another part, relatively fixed abutment means to hold said cam ring against rotation with the platen, and a plurality of adjustment connections between said cam ring and said abutment means whereby the eccentric portion of said cam slot may be shifted to a plurality of circumferential positions about the platen.

11. In a typewriter or like device utilizing a rubber or rubber-like platen, a pin feed device including a band having a relatively snug fit on the platen but movable lengthwise thereof, feed pins carried by said band for rocking motion between retracted and projected positions, a cam mounted on said band and engageable with said pins to control the movement of said feed pins, and a pronged device carried by said band to be anchored in the material of the platen for holding the pin feed device in a selected position of adjustment on the platen.

12. A typewriter or like device, including a platen, a pin feed device on said platen including a band in surrounding relation to the platen and infinitely adjustable along the length of the platen, means for anchoring said band relatively to said platen in selected positions of adjustment, oscillatory feed pins carried by said band, a cam associated with said band for unison longitudinal and relative rotary motions, said feed pins engaging said cam and rocking under the control thereof in response to relative rotary motion between said band and said cam, and means for holding said cam from rotating with said platen.

13. A typewriter or like device according to claim 12, characterized in that said last named means includes mechanism for setting said cam to varying rotary positions of adjustments whereby to vary the oscillatory action of the feed pins with respect to the phase rotation of the platen.

ALBERT W. METZNER.
